Primary Examiner — Mark A Goodwin

(57) **CLAIM**

The ornamental design for a leaf shattering machine, as shown and described.

DESCRIPTION

FIG. 1 is a perspective view of a leaf shattering machine showing my new design;

FIG. 2 is another perspective view thereof;

FIG. 3 is a front elevation view thereof;

FIG. 4 is a back elevation view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings illustrate portions of the leaf shattering machine and form no part of the claimed design.
